CLAIM

The ornamental design for a hydraulic power pack, as shown and described.

DESCRIPTION

FIG. 1 is a perspective view of a hydraulic power pack; FIG. 2 is a right side view of the hydraulic power pack; FIG. 3 is a left side view of the hydraulic power pack; FIG. 4 is a front elevational view of the hydraulic power pack;

FIG. 5 is a rear elevational view of the hydraulic power pack; and,

FIG. 6 is a top plan view of the hydraulic power pack. The broken lines shown represent the portions of the hydraulic power pack that form no part of the claimed design.

1 Claim, 6 Drawing Sheets
